(57) **CLAIM**

The ornamental design for a security video storage base station as shown and described.

DESCRIPTION

FIG. 1 is a front bottom perspective view of a security video storage base station showing our new design;

FIG. 2 is a rear top perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is an enlarged view of the encircled portion 9 indicated in FIG. 1; and,

FIG. 10 is an enlarged view of the encircled portion 10 indicated in FIG. 2.

The evenly dashed broken lines depict portions of the security video storage base station that form no part of the claimed design. The long dash short dash broken lines in FIGS. 1, 2, 9, and 10 indicate cutoff boundaries for enlarged detail portion views in FIGS. 9 and 10 and form no part of the claimed design.
